UNITED STATES PATENT OFFICE.

JOHANNES GERARD FREDERIK ROOKER, OF VRYENBAN, NEAR DELFT, NETHERLANDS, ASSIGNOR TO FIRMA A. DE JONG, SCHEEPSWERF EN MACHINEFABRICK, OF VLAARDINGEN, NETHERLANDS, A CORPORATION OF THE NETHERLANDS.

EMBROIDERING-MACHINE.

1,348,054.

Specification of Letters Patent. Patented July 27, 1920.

Application filed May 24, 1917. Serial No. 170,682.

To all whom it may concern:

Be it known that I, JOHANNES GERARD FREDERIK ROOKER, a subject of the Queen of the Netherlands, residing at Vryenban, 5 near Delft, Netherlands, have invented certain new and useful Improvements in Embroidering-Machines, of which the following is a specification.

The invention relates to a embroidery-machine for automatically sewing characters, words, figures, numbers, etc., in woven materials and the like.

In using a machine according to the invention marking occurs very fast, whereby 15 the characters, figures or the like are always quite uniform.

The usual sewing by hand of characters in woven materials or embroidering or marking characters by hand in clothes, 20 which consumes much time, now is avoided and made superfluous.

The machine particularly is arranged in such a manner, that a predetermined character, figure, word or number can be sewed 25 once in a piece of material or more than once subsequently in different pieces of material, whereby the machine needs to be adjusted but once. It is also possible, in adjusting the machine but once, to sew a predetermined character, figure, word or number 30 in different pieces of material; if desired a series of characters can also be sewed with the machine.

The machine according to the invention 35 consists in the combination of a shoemakers-sewing-machine known in itself, with a device automatically effecting the angular adjustment of the known feed claw of the sewing-machine, according to the character, 40 figure, word or number to be sewed in the piece of material, which device, after the mark has been finished, is automatically returned in its initial position and stops the sewing-machine. This device consists of 45 two chief elements namely a device with which the usual feed claw of the shoemakers-sewing-machine is adjusted in such a manner that the desired character or the like is sewed, and an automatical stopping- 50 device, by means of which the machine is stopped and at the same time the different members are returned in the initial position. The first chief element according to the invention consists of a rotatable, gradu-

ally driven drum, on the surface of which 55 longitudinal adjacent rows of longitudinally slidable blocks are arranged, said blocks being provided with more or less deep recesses and more or less high teeth between the recesses, said teeth and recesses of 60 one or more blocks corresponding to a character or figure, that the movements, transmitted to the feed claw of the sewing-machine, of a pin, alternatively falling in those recesses or on those teeth and moved 65 back again, impart to the feed claw the desired angular adjustment.

In order, after the mark has been sewed in the piece of material to return the drum to its initial position, whereby at the same 70 time the machine is stopped, the drum, according to the invention, may be provided with adjustable stops or notches, which, after the mark has been finished, effect the stopping of the sewing-machine and the re- 75 turning of the drum in its initial position.

The invention will be fully explained hereinafter by the aid of the accompanying drawings in which:

Figure 1 is a top view of the machine.

80

Fig. 2 a side elevation with parts broken away.

Fig. 3 a section on the line 3—3 of Fig. 1, parts being broken away.

Fig. 4 a section on the line 4—4 of Fig. 1. 85

Fig. 5 a detail of the machine.

Fig. 6 is a section on the line 6—6 of Fig. 1, and

Fig. 7 is a fragmentary side elevation, showing the gearing operated by the movements of the pin-operated rod for operating the claw. 90

The machine, mounted on the frame, is driven by means of a pulley 1 on a horizontal shaft 2. By means of a sliding clutch 95 3 the shaft 2 can be coupled with a hollow shaft 4 surrounding the shaft 2. On the shaft 4 is fixed a bevel-wheel 5 engaging a bevel-wheel 6 on a shaft 7. The rotation of the shaft 7 is transmitted by means of a cam-disk 8 to a lever 9, fixed on one end of a shaft 10 (Fig. 1). The angular rotations of shaft 10 are transmitted by means of a lever 11, secured to one end of the shaft 10 and having its other end connected with the 105 horizontally slidable rod 12. The rod 12 transmits its movements to a vertical pin 13 by means of a rack 20 (Fig. 3) on the rod

12, a toothed sector 21, a gearwheel 22 fixed on the shaft of the toothed sector and a toothed rack 23 fixed to the pin 13. The cam of the cam disk 8 in engaging the free 5 end of the lever 9, lifts this lever. Consequently the rod 12 is moved to the left and the pin 13 is moved upward. A spring *a* at the right end of the rod 12 moves this rod back to the right and consequently the pin 10 downward as soon as the lever 9 is freed from the cam of the cam disk. The function of the pin 13 will be fully described hereinafter. First however it must be mentioned that also the movement of a cylinder or drum 15 16 (Fig. 4) is derived from the shaft 7 by means of a crank 14, a rod 15, a lever 17 freely rotatable about the axis of the drum and a pawl 18 connected with the lever 17 and engaging a ratchet-wheel 19 fixed on the 20 drum-shaft. Each revolution of the shaft 7 with cam disk 8 causes a rotation of the drum of one tooth of the ratchet-wheel.

The drum carries a plurality of adjacent rows of blocks 68 being slidable lengthwise 25 for example in dove-tailed longitudinal grooves of the drum surface. This plurality of blocks serves to make various character—or figure combinations. Each block is provided with one or more recesses 69 (Fig. 30) of different depth between which are provided teeth of different height. The pin 13 above the drum can be brought into engagement with these recesses and teeth. According to the pin falling into a more or less 35 deep recess or on a tooth between two recesses, the rod 12 will be moved more or less to the right by the spring. These movements of the rod 12 are transmitted in a manner to be described hereinafter to the feed 40 claw 70 of the sewing-machine 63 and impart to this claw the desired angular adjustment. It may be mentioned here, that the sewing-machine 63 is driven by means of a chain-pulley 64 on the shaft 4, a chain 65 45 and a chain-pulley 66 on the shaft *b* of the sewing-machine, so that the latter is stopped by disengaging the clutch 3.

The downward movements of the pin 13 determine the angular adjustments of the 50 feed claw to be obtained. Owing to the fact that these downward movements are determined by the blocks and that the latter are shaped in correspondence with the figure, character, etc., to be sewed, the feed claw of 55 the sewing-machine receives such an angular corresponding adjustment that the desired figure, character, etc., is sewed in a piece of material or the like.

It will be clear, that the cam disk 8 and 60 the crank 14 must be adjusted with respect to each other in such a manner that the pin 13 is kept lifted when the ratchet wheel 19 is moved forwardly by a tooth by the pawl 18 and consequently the blocks are rotated 65 correspondingly.

The movements to the left and to the right of the rod 12 can be transmitted directly to the feed claw of the sewing-machine. Preferably however a device is interconnected between the pin and claw, which effects the displacement of the claw, which as is known is obtained by a rotation of a gearwheel. An enlarged transmission is to be preferred over a direct one, as then the blocks can be smaller and the mechanism directly coöperating therewith has to transmit less power, so that the whole machine then works more accurately. 70 75

This device consists of a block 24 (Figs. 1, 3 and 6) provided at its upperside with an oblique cam 25 and at its lowerside with a vertical rib 26 parallel with the rod 12. The block 24 is slidable perpendicular to the rod 12 in a recess 27 of an enlarged part of this rod. A movement of the rod 12 causes the cam 25 to slide through an oblique slot 28 of an enlarged part 29 of a rod 30, arranged perpendicular to the rod 12 and slidable longitudinally, said rod 30 then being frictionally held against displacement. 80 85 90

The slot 28 is arranged at a considerably smaller angle with the rod 12 than with the rod 30, so that a movement to the right of the rod 12 by the spring *a* will displace the block in the recess 27, whereby the cam 95 slides through the slot 28. The block consequently is moved out of its middle-position (that is with the cam in a vertical plane through the axis of the rod 12) by a movement to the left as well as to the right. 100 The displacement of the rod 30, acting on the feed claw of the sewing-machine by means of a gearing 71 is effected by the device shown in Fig. 5.

This device consists of a cam disk 31, 105 driven by the shaft 2, with two cams 32 and 33 in different vertical planes, said cams acting respectively on the ends of weighted arms 34 and 35 of angle-levers, the other arms 36 and 37 of which act on the rib 26 110 of the block 24 between the free ends of said arms. A spring *C* connected with the arms 34 and 35 holds said arms in engagement with the cams 32 and 33. The cams are so shaped and the angle-levers are arranged in such a manner that the arms 36, 37 move the rib back to the middle-position from the position into which it has been moved by the pin movement. 115

The cam 25 in the slot 28 hereby will 120 move the rod 30 lengthwise, said rod, by means of the transmission 71, imparting to the feed claw the corresponding angular adjustment.

The second chief-element of the machine 125 is the automatical stopping-device.

Every time that a character, figure, word or the like has been sewed in the piece of material by one or more subsequent pin movements and the transmission thereof to 130

the feed claw of the sewing-machine, the drum with the blocks is rotated a certain angle by the pawl 18 and, for sewing this character, figure, word or the like again, 5 must be returned in its initial position. This is effected automatically. For this purpose a pulley 38 with a weight 39 is fixed on the drumshaft (Figs. 1 and 4). For rotating back the drum, the pin 13 must 10 be kept in its lifted position. The pawl 18 also must be kept lifted out of engagement with the ratchet wheel 19. A counterpawl 40 arranged to engage the ratchet wheel 19 in order to prevent the drum from rotating 15 backward must also be lifted out of engagement with the ratchet wheel.

For keeping the pin 13 uplifted, stopping the machine and lifting the two pawls 18 and 40 the following device is employed: 20 A block 68 is provided with an adjustable projection 41. This projection is secured to a block of the row in the same vertical plane with the tail 42 of lever 44 rotatable about the shaft 43 and provided with a 25 weight at its other end.

This lever acts on two stops 45 and 46 of a sector 47, freely rotatable about the axis of the lever. In the position shown in Figs. 1 and 4 the lever 44 bears against the 30 projection 45. This is the position in which the clutch 3 is coupled, the machine is running and the drum is moved forward by the pawl 18.

The projection 41 in engaging the tail 42 of the lever 44 will turn the latter, so that it falls against the projection 46 and consequently will turn the sector 47.

Together with the lever 44 a sector 72 fixed on the shaft of the lever 44 is rotated. 40 This sector lifts the counterpawl 40 by means of a connecting rod 48 and a rod 49 on the axis of the pawl, connecting 48 with some play with the pawl.

An elongation 50 of the sector 72 when 45 the sector rotates presses on the tail 51 of the pawl 18, so that this pawl also is lifted. The sector 47 is articulated at 52 to one end of a rod 53 (Fig. 3), the other end of which is articulated to a rod 55 fixed on the same 50 shaft as the lever 54 of the clutch 3.

In rotating the sector 47 to the right the clutch 3 consequently is disengaged and the machine is stopped. On the same shaft as the rod 55 is fixed a lever 56, the end of 55 which is articulated to an arm of a double-armed lever 58, rotatable at 57, the other arm of which, in rotating to the left, comes into engagement with a stop 59 of the rod 12 so that this stop and consequently the 60 rod 12 are moved to the left and the pin 13 is lifted out of engagement with the blocks of the drum. The drum now is freed from the pawls 18 and 40 as well as from the pin 13, and is rotated back in its initial position by the weight 39. After the return

of the drum to initial position a second adjustable stop 60 on the surface of the drum in a vertical plane other from that of the stop 41 comes into engagement with an arm 73 on the shaft of the lever 44 and turns 70 the latter back against the stop 45. In order to prevent the automatical coupling of the clutch 3 under the action of the lever 44 with weight on the stop 45 of the sector 47, a stop 61 is arranged in the path of the 75 lower end of the lever 54 (Fig. 3), said stop keeping said lower end in the disengaged position. This stop can be moved by hand, by means of a lever 62 under the action of a weight or spring, out of the path of the 80 lower end of the lever 54, so that the clutch again is coupled, the rod 12 again is moved to the right, the pin is brought into engagement with a block and the pawls are coupled. 85

Claims.

1. In an embroidering machine, the combination with a sewing machine having a feed claw, of a drum having on its periphery depressions and projections representing characters to be sewed, means for rotating the drum, a vertically slidable pin adapted to engage the projections and depressions of the drum, means for raising and lowering the said pin, and means for adjusting the feed claw of the machine from the pin operating means. 90

2. In an embroidering machine, the combination with a sewing machine having a feed claw, of a drum having on its periphery depressions and projections representing characters to be sewed, means for rotating the drum, a slidable member adapted to engage the depressions and projections of the drum, means for controlling the movement of the 100 slidable member, means for adjusting the feed claw of the machine from the member controlling means, and means for returning the drum to its initial position and stopping the machine. 110

3. In an embroidering machine, the combination with a sewing machine having a feed claw, of a rotatable drum having on its periphery depressions and projections, a sliding pin adapted to engage the depressions 115 and projections of the drum, a sliding and spring actuated rod, means for operating the pin from said rod, means for operating the rod from the sewing machine, and means for adjusting the feed claw of the 120 machine from the said rod.

4. In an embroidering machine, the combination with a sewing machine having a feed claw, of a drum having on its periphery depressions and projections, a sliding pin 125 adapted to engage the projections and depressions of the drum, a sliding and spring actuated rod, means for operating the pin from the rod, means for operating the rod, a block mounted on the said rod and having 130

- 4
- an oblique cam on its upper face, a second rod at right angles to the first rod and having an enlarged portion provided with an oblique slot into which the cam of the block works, and a connection between the second rod and the feed claw of the machine for adjusting the same.
5. In an embroidering machine, the combination with a sewing machine having a feed 10 claw, of a drum having on its periphery depressions and projections, a sliding pin adapted to engage the projections and depressions of the drum, a sliding and spring actuated rod having an enlarged slotted 15 portion, means for operating the pin from the rod, means for operating the rod, a block mounted on the enlarged portion of the rod and having a rib projecting through the slot of said rod and an oblique cam on its 20 upper face, a second rod at right angles to the first rod and having an enlarged slotted portion into which the cam of the block extends, a connection between the second rod and the feed claw of the machine, a disk 25 having two cams, means for operating the disk, and angle levers operated by the cams of the disk and adapted to alternately engage the rib of the block to operate the latter.
30. 6. In an embroidering machine, the combination with a sewing machine having a clutch, of a rotatable drum having projections, a ratchet wheel on the shaft of the drum, pawls engaging the ratchet wheel, a 35 shaft, a weighted lever mounted on the shaft and adapted to be engaged and turned by said projections, a sector on the shaft of the lever and provided with two stops adapted to be engaged by the lever, a 40 connection between the sector and the clutch of the machine, a second sector on the shaft of the said lever and provided with an extension adapted to engage one of the pawls to disengage it from the ratchet wheel, and 45 a link connection between the second sector and the other pawl to disengage it from the ratchet wheel.
7. In an embroidering machine, the combination with a sewing machine having a 50 clutch, of a shaft, a rotatable drum on the shaft and having projections, a ratchet wheel on the shaft of the drum, pawls engaging the ratchet wheel, means for operating one of the pawls to turn the ratchet wheel, a lever shaft, a weighted lever mounted on the lever shaft and adapted to be engaged by the projections of the drum, a sector on the lever shaft and provided with

two projections adapted to be engaged by the lever, a clutch lever, a connection between the sector and the clutch lever, a second sector on the said lever shaft and provided with an extension adapted to engage the pawl which operates the ratchet wheel to disengage it from the same, a link connecting the second sector with the other pawl which prevents backward movement of the ratchet wheel, and a stop for engaging the clutch lever to hold the clutch disengaged.

8. In an embroidering machine, the combination with a sewing machine having a feed claw, of a rotatable pattern drum, a slidable pin for engaging said drum, a sliding and spring pressed member, means for 70 operating the member, means for operating the said pin from the member, a second member at right angles to the first member and having a connection therewith, means whereby the second member is moved in direction of its length, and means for adjusting the feed claw from the second member.

9. In an embroidering machine, the combination with a sewing machine having a feed claw, of a pattern drum, a sliding pin 85 for engaging the drum, a sliding and spring pressed member, means for operating the member, means for operating the pin from the member, a second member at right angles to the first member, a cam operated by 90 the first member and engaging the second member, means for operating the cam, and means for adjusting the feed claw from the said second member.

10. In an embroidering machine, the combination with a sewing machine having a feed claw, of a rotatable drum having on its periphery depressions and projections, a sliding pin provided with a rack and adapted to engage the depressions and projections 100 of the drum, a sliding and spring actuated rod provided with a rack, a toothed sector engaging the rack of the rod, a gear wheel on the shaft of the sector and meshing with the rack of the pin, means for operating the 105 rod from the sewing machine, and means for adjusting the feed claw of the machine from the said rod.

In testimony whereof I have hereunto set my hand in presence of two subscribing 110 witnesses.

JOHANNES GERARD FREDERIK ROOKER.
